[57] **CLAIM**

The ornamental design for a serving table, substantially as shown.

DESCRIPTION

FIG. 1 is a front perspective view of a serving table showing my new design;

FIG. 2 is a bottom plan view thereof;

FIG. 3 is a side elevational view thereof;

FIG. 4 is a side elevational view thereof taken from the side opposite that shown in FIG. 3;

FIG. 5 is a rear elevational view thereof; and

FIG. 6 is a front perspective view thereof with the sliding table top in its open position.
